UNITED STATES PATENT OFFICE.

REXFORD C. GLOVER, OF FLINT, MICHIGAN, ASSIGNOR TO GENERAL MOTORS CORPORATION, OF DETROIT, MICHIGAN, A CORPORATION OF DELAWARE.

STRAIGHTENING MACHINE.

Application filed September 24, 1924. Serial No. 739,589.

This invention relates to machines for straightening clutch disks and similar articles, and is illustrated as embodied in a modification of a standard drill press. Preferably the disks are straightened by rolling them in such a manner as to flex various portions of the disk back and forth, to straighten out any warped or bent parts.

In one desirable arrangement, there are two novel floating, or freely-rotatable, sets or units of rollers, engaging respectively the upper and lower surfaces of the clutch disk, the rollers of one set preferably being staggered with respect to those of the other set, to secure the described flexing action. In order to provide for readily inserting and withdrawing the disks, the parts on the opposite sides of the disk may be arranged to be separated axially of the disk, and in the arrangement illustrated in the drawings these parts are arranged in a novel manner such that they are automatically brought into operative inter-engagement by their return to the working position. I find it advantageous in practice to use conical rollers supported by upper and lower conical tracks, so that a very heavy pressure may be exerted on the disks without any binding of the moving parts.

The above and other objects and features of the invention, including various novel combinations of parts and desirable particular constructions, will be apparent from the following description of one illustrative embodiment shown in the accompanying drawings, in which:

Figure 1 is a side elevation of a drill press modified to embody my invention;

Fig. 2 is a view of the operating parts, partly in central vertical section and partly in front elevation; and

Fig. 3 is a horizontal section on the line 3-3 of Fig. 2, showing the lower set of rollers.

As noted above, I find it convenient to embody my invention in a modification of a standard drill press including an adjustable base 10, and a vertical standard 12 having an upper arm 14 for the support of a power-driven shaft 16 driving through bevel gears 18 a sleeve keyed to a vertical driven shaft 20 raised and lowered by a rack sleeve 22 and a pinion having an operating lever 24 supported on a lower arm 26 of the standard 12.

The clutch disk "D" is supported by a series of conical rollers 30 engaging its lower surface, the rollers being supported by rolling on a conical track 32 secured by machine screws 34 to a plate 36 carried by the base 10. Each roller is journaled on a spindle 38 projecting inwardly from a ring 40, a thrust bearing 42 preferably being provided at the base of the roller. Rotatably mounted on a thrust bearing 44 on track 32 is a bed 46, having fingers 48 entering the usual notches in the edge of disk "D". Thus bed 46 serves as means for rotating the disk about its axis.

Bed 46 has clutch teeth 50 on its upper surface which, when rack 22 is in its lowest position, are engaged by teeth 52 on the bottom of a driving member 54 secured by machine screws 56 to a part 58 driven by shaft 20. Member 54 has a guide or pilot 60 projecting axially into a central cylindrical opening in the bed 46.

The upper surface of the disk is engaged by conical rollers 62, rotatably mounted as described for rollers 30 on spindles projecting inwardly from a ring 64. Rollers 62 are supported, to be easily rotatable under heavy pressure, by a conical track 66 secured to a part 68 backed up by a thrust bearing 70 resting against a flange of part 58. The rollers 62 are staggered with respect to rollers 30,—i. e. each roller 62 comes between two rollers 30. To insure the maintenance of this relation, rings 40 and 64 are connected by pins 72 secured to ring 64 and 90 slidable in vertical bores formed in ring 40.

It will be seen that ring 40 and rollers 30 constitute a lower floating or freely-rotatable set or unit, and that similarly the ring 64 and its rollers 62 constitute an upper floating or freely-rotatable set or unit.

In operation, with the upper parts separated from the lower parts as shown in Fig. 1, a clutch disk is laid by the operator on rollers 30 with its notches in engagement with fingers 48. Lever 24 is then operated to lower the upper parts, including the driving member 54 and the upper rollers 62, thus clamping the disk firmly between the upper and lower rollers. As the disk is rotated, it pulls the rollers around with it, causing them to roll on its upper and lower surfaces, thus causing a rapid flexing back and forth of all parts of the disk, completely ironing out any warped or distorted parts.

While one embodiment of the invention has been described in detail, it is not the intention to limit its scope to that particular embodiment, or otherwise than by the terms 5 of the appended claims.

I claim:

1. A machine comprising, in combination, a rotatably mounted lower member having a clutch portion and which is constructed and 10 arranged to engage and rotate a clutch disk, a freely rotatable unit of a plurality of rollers engaging the lower surface of the disk, a vertically movable power-rotated upper member having a clutch portion arranged 15 to engage and drive the clutch portion of the lower member when in its lowest position, and a second freely rotatable unit of rollers arranged for vertical movement with the upper member and engaging the upper 20 surface of the disk when in their lowest position.

2. A machine as defined by claim 1, in which the upper and lower roller units are 25 connected to rotate together but in a manner permitting their separation vertically.

3. A machine comprising, in combination, a rotatably mounted lower member having a clutch portion and which is constructed and arranged to engage and rotate a clutch 30 disk, a freely rotatable unit of a plurality of conical rollers engaging the lower surface of the disk, a conical track supporting the rollers, a vertically movable power-rotated upper member having a clutch portion arranged 35 to engage and drive the clutch portion of the lower member when in its lowest position, a second freely rotatable unit of conical rollers arranged for vertical movement with the upper member and engaging the upper surface of the disk when 40 in their lowest position, and a second conical track supporting the upper rollers and vertically movable with them.

4. A machine comprising, in combination, 45 a rotatably-supported bed having clutch teeth on its upper surface and having fingers on its edge arranged to enter notches in the edge of a clutch disk to drive the disk, a lower floating annular ring surrounding the bed, a series of conical rollers rotatably supported by the ring and having rolling engagement with the lower surface of the disk, a conical track supporting the rollers, a rotatable driving member having on its lower 50 surface clutch teeth engageable with the teeth of the bed, an upper floating ring surrounding the driving member, an upper series of conical rollers rotatably supported by the upper ring and having rolling engagement with the upper surface of the disk, an upper conical track supporting the upper rollers, and means for relatively axially moving the driving member and upper ring 55 and rollers and track, on the one hand, and the bed and lower ring and rollers and track, 60

on the other, to permit the removal and insertion of clutch disks.

5. A machine as defined by claim 4, in which the upper and lower rings are connected to rotate together, and the upper rollers are staggered with respect to the lower rollers. 70

6. A machine comprising, in combination, a rotatably-supported bed having clutch teeth on its upper surface and having fingers 75 on its edge arranged to enter notches in the edge of a clutch disk to drive the disk, a lower floating annular ring surrounding the bed, a series of rollers rotatably supported by the ring and having rolling engagement 80 with the lower surface of the disk, a rotatable driving member having on its lower surface clutch teeth engageable with the teeth of the bed, an upper floating ring surrounding the driving member, an upper 85 series of rollers rotatably supported by the upper ring and having rolling engagement with the upper surface of the disk, and means for relatively axially moving the driving member and upper ring and rollers, 90 on the one hand, and the bed and lower ring and rollers, on the other, to permit the removal and insertion of clutch disks.

7. A machine comprising, in combination, means to rotate a clutch disk about its axis, 95 upper and lower rotatable sets of rollers staggered as regards the individual rollers of each set, said rollers being revoluble about the axis of rotation of the disk and means for rotatably supporting said rollers. 100

8. A machine comprising, in combination, means to rotate a clutch disk about its axis, a set of rollers engaging the upper surface of the disk, another set of rollers staggered with respect to the rollers of the first set 105 and engaging the lower surface of the disk, both sets of rollers being rotated as a unit by power derived from the disk and means for rotatably supporting said rollers.

9. A machine comprising, in combination, 110 means to rotate a clutch disk about its axis, upper and lower rotatable sets of rollers staggered with respect to each other, upper and lower non-rotatable tracks upon which the rollers revolve, said rollers engaging opposite surfaces of said disk and being driven therefrom and means for rotatably supporting said rollers.

10. A machine comprising, in combination, means to rotate a clutch disk about its 120 axis, upper and lower rotatable sets of rollers staggered with respect to each other, upper and lower non-rotatable tracks upon which the rollers revolve, both sets of rollers being revolved as a unit by power derived 125 from the disk and operative to straighten it and means for rotatably supporting said rollers.

In testimony whereof I affix my signature.
REXFORD C. GLOVER.
